CLAIM

The ornamental design for an applicator container, as shown and described.

DESCRIPTION

FIG. 1 is a perspective view of an applicator container, showing the top, a side and the front of our new design, wherein the cover is attached to the front of the head;

FIG. 2 is a front elevational view of the applicator container of FIG. 1;

FIG. 3 is a rear elevational view of the applicator container of FIG. 1;

FIG. 4 is an elevational view of the right side of the applicator container of FIG. 1, the other side being a mirror image;

FIG. 5 is a top plan view of the applicator container of FIG. 1;

FIG. 6 is a bottom plan view of the applicator container of FIG. 1; and,

FIG. 7 is an exploded perspective view of the applicator container, wherein the cover is shown detached from the front of the head.
